CLAIM

The ornamental design for microphone accessory, substantially as shown and described.

DESCRIPTION

FIG. 1 is a perspective view of a microphone accessory as seen from the front, top, and left side;

FIG. 2 is a left side view thereof;

FIG. 3 is a front view thereof;

FIG. 4 is a right side view thereof;

FIG. 5 is a back view thereof;

FIG. 6 is a top view thereof; and,

FIG. 7 is a bottom view thereof.

The dotted line portions of the drawings represent environmental structure only and do not form part of the claimed design.

The microphone cord is shown with a symbolic breaks in its length. The appearance of any portion of the article between the break areas form no part of the claimed design.

1 Claim, 7 Drawing Sheets
